UNITED STATES PATENT OFFICE.

FREDERIC P. GATES, OF WEST HARTFORD, CONNECTICUT, ASSIGNOR TO THE HART MANUFACTURING COMPANY, OF HARTFORD, CONNECTICUT, A CORPORATION OF NEW JERSEY.

ELECTRIC SWITCH.

Application filed April 22, 1922. Serial No. 555,997.

This invention relates generally to electric switches of the type having a rotary handle for moving suitable poles or switch plates relative to terminals held on a base, and the handle constituting a pointer for indicating the indexed positions of the switch poles. In switches of this type, it is usually required that the handle stand in certain angular positions with reference to the axis of the switch; for instance, that the handle be vertically and horizontally disposed in its respective indexed positions. However, in order to supply the demands based on different requirements and specifications of the trade, it is necessary to provide switches disposed in different angular relations on their bases; for instance, some switches will have their terminals disposed as shown by dotted lines, Fig. 2, while others will be turned say at 40° about their axes, so that their terminals will be disposed along the dot and dash lines of this figure.

The aim of the present invention is to provide a new and advantageous arrangement for adapting switch handles of a single construction for use in meeting these various demands and requirements, thus eliminating the necessity of manufacturing and carrying in stock a different structure of handle for each angular disposition of switch. Further features of novelty and advantage residing in the present invention will be pointed out hereinafter more in detail.

In the accompanying drawings, wherein I have shown for illustrative purposes one embodiment which the invention may take,—

Fig. 1 is a sectional view taken vertically and centrally through the switch shown in Fig. 2;

Fig. 2 is a plan view;

Fig. 3 is a central, sectional view through the handle taken on line 3—3 of Fig. 5;

Fig. 3^a is a partial sectional view taken through the handle;

Fig. 4 is a bottom view of the handle proper;

Figs. 5, 5^a and 5^b are views similar to Fig. 4 but showing the respective washers secured to the handle for determining the angular position of the handle on the switch spindle;

Fig. 6 is a perspective view of a collar for securing the washers in place.

In Fig. 1 of the accompanying drawings, I have shown so much of a switch of the type illustrated in the patent to Smart and Gates, S. No. 1,409,146, dated March 7, 1922, as is necessary to make clear one application of the present invention. This showing is, of course, by way of illustration only, and it is not to be taken as restrictive of or as having any limiting effect upon the present invention, it being obvious that the novel features herein described may be applied to and incorporated in switches other than of the particular kind or type disclosed, and that these features are susceptible of various modifications, changes and adaptations without departing from the spirit of the invention. For a complete understanding of the construction and operation of this Smart and Gates switch, the said patent may be referred to. A very brief statement as to its operation will here be given, so that the application of the hereinafter described improvements of the present invention will be clear.

Referring to the drawing in detail, 10 is a base of insulating material and of any desired shape on which are fixed terminals 11, suitably spaced apart, say at 90°, as shown. Journaled in the bearing 13 is a spindle 14, loose on which is a switching unit 15 having suitable switch or pole plates 16, insulated from one another and arranged to connect the terminals 11 in various combinations, the present arrangement being such that the switch may be turned into high, medium, low or off positions. Secured to the switching unit 15 and loosely receiving the spindle 14 is an abutment 17. Secured to the spindle is a U-shaped spring plate 19, having an upwardly extending projection 20 adapted to be operatively connected to the handle 21, as hereinafter described more in detail. Coiled about the spindle 14 and having its ends straddling the spring plate and abutment, is a spring 22. In operation, the handle may be turned step by step in either direction to effect the desired connections between the terminals. When the handle is thus turned, the spring 22 is placed under tension until the catch plate 23 is released from the stop plate 24, and

then the spring throws the switching unit one step with a quick movement, and the catch plate re-engages the stop plate to stop the switching unit in its new indexed position.

The handle 21, which may be of any suitable material, but preferably of porcelain, is provided with a bore or well 30, having longitudinally extending grooves 31 which receive the guides or wings 32 of a connector or sleeve 33 internally threaded to receive the upper threaded end of the switch spindle 14. The handle is normally held against longitudinal movement relative to the sleeve by a spring 34 abutting against a collar 35 loosely receiving the sleeve 33, and held in place by a spring ring 36 sprung into an annular groove in the wall of the bore adjacent its open end. Heretofore it has been the custom to provide the switch handle with a single notch or recess 38 for receiving the projection, and thus fixing the handle against rotation on the spindle.

In accordance with the present invention, provision is made for connecting handles of identical construction to the switch spindles in various angular positions corresponding to the angular positions of the respective switches on their bases, and thus making it possible to meet from a single stock of handles the requirement that the handles of the several switches extend in the desired directions in their indexed positions. To this purpose, the handle is provided at its inner end with a plurality of notches 38, 38^a and 38^b, adapted to receive the projection 20 and spaced apart in accordance with the angular disposition of the various switches on their bases; and means, in the form of washers 40, 40^a and 40^b, are provided for selectively blanking all but one of the notches. The washers may be secured to the handle in any suitable manner, but, by preference, in order to accomplish economy in manufacturing and facility in assembling, the collar 35 is provided with a pair of spaced ears 42, and each of the washers has a pair of slots 43 for receiving these ears, the ears being turned over the washers, as shown in Fig. 3, so as to hold them in place. It will be noted that the collar, together with the washers secured thereto, is non-rotatable relative to the porcelain handle.

In the present illustrative disclosure of the invention, it may be assumed that requirements of the trade demand three different models of switches,—one model having its terminals disposed as shown by dotted lines, Fig. 2; the second model turned 40° counter clockwise relative to the first one, so that it will have its terminals disposed on the dot and dash lines *a—a*; and the third model turned 30° clockwise relative to the first one, so that it will have its terminals dis-

posed on the lines *b—b*. Under this assumption, the recesses 38, 38^a and 38^b will be spaced apart at 40°. When the handle is to be applied to a switch of the first model,—that is, with its terminals disposed as shown by dotted lines, Fig. 2,—the washer 40 will be secured to the handle as shown in Figs. 3 and 5. It will be seen that the opening 41 of this washer registers with the notch 38 of the handle, and that the washer blanks the other notches 38^a and 38^b. To secure the handle in place, the porcelain handle is drawn outwardly against the tension of the spring 34 and the handle is turned so as to screw the sleeve onto the threaded spindle; and after the washer has been brought into engagement with the cover 44 of the switch the handle is released, so that the notch 38 will receive the projection 20, as shown in Fig. 3. When the handle is to be applied to a switch of the second model,—that is a switch having its terminals disposed on the lines *a—a* of Fig. 2, the washer 40^a will be secured to the bottom of the handle, as shown in Fig. 5^a. This washer has an opening 41^a adapted to register with the aperture 38^a. When the handle is to be applied to a switch of the third model,—that is, a switch having its terminals disposed along the line *b—b* of Fig. 2,—a washer 40^b having an aperture 41^b adapted to register with the notch 38^b will be secured to the handle, as shown in Fig. 5^b. It will be noted from Fig. 1 that the spring 34 yieldingly urges the handle towards the switch base, and thus presses the washer 40 against the cover 44, whereby the latter is maintained in place without employing screws or other similar attaching means. The washers are preferably of fibre or like material, and therefore have a smooth, relatively soft surface engaging the switch cover, so that when the handle is turned the bearing between the bushing and the cover is such that there is little or no friction, scratching or noise.

I claim as my invention:—

1. In combination with a rotary switch spindle, a handle member constituting a pointer and having a plurality of means for securing it to various angular positions against rotation on the spindle, and means for selectively rendering all but one of said first mentioned means ineffective.

2. In combination with a rotary switch spindle having a projection, a switch handle having a plurality of angularly spaced recesses or notches adapted to receive said projection, screw threaded means for connecting the handle to said spindle, and means mounted on the handle for blanking all but one of said recesses.

3. A handle for use in connection with switches having a rotary spindle provided with a projection, and including a handle

member having a plurality of means adapted to co-operate with said projection for holding said handle against rotation relative to the spindle, and means for rendering all of said means except one ineffective.

4. A handle, for use in connection with switches having a rotary spindle provided with a projection, and including a handle member having angularly spaced recesses positioned to receive said projection, means for connecting said handle member to said spindle for rotary and longitudinal movements, and a member blanking all but one of said recesses.

5. A handle, for use in connection with switches having a rotary spindle provided with a projection, and including a handle member provided with a plurality of angularly spaced recesses positioned to receive the projection, means for connecting said

member for sliding and rotary movements to the spindle, a washer having a single aperture adapted to register with one of said recesses, and means for securing said washer to said handle member.

6. A handle for use in connection with switches having a rotary spindle provided with a projection, and including a handle member having a bore and a plurality of angularly spaced recesses adapted to receive the projection, a connector slidably mounted in said bore and held against rotation relative to said handle, a spring normally holding the handle member against longitudinal movement relative to the connector, a washer adapted to blank all but one of said recesses, and means for retaining the spring and connector within the recess and securing said washer to said handle.

FREDERIC P. GATES.
